UNITED STATES PATENT OFFICE.

CHARLES DOERING, JR., OF CHICAGO, ILLINOIS.

CAN-WASHING MACHINE.

1,149,813.

Specification of Letters Patent. Patented Aug. 10, 1915.

Application filed May 25, 1914. Serial No. 840,667.

To all whom it may concern:

Be it known that I, CHARLES DOERING, Jr., a citizen of the United States, and resident of Chicago, in the county of Cook and State of Illinois, have invented certain new and useful Improvements in Can-Washing Machines, of which the following is a description, reference being had to the accompanying drawings, which form a part of my specification.

My invention relates to a machine more especially intended for use in washing ice cream cans, namely cans provided with cylindrical side walls of the character disclosed in the drawings.

The object of my invention is to provide a machine of the character referred to, which is adapted to scrub or clean cans of various sizes, both in length and diameter, commensurate with the particular size of machine; the machine being adapted to clean both the inside and outside surfaces of the can at one and the same time.

Another object of my invention is to provide a machine wherein the scrubbers or can cleaning members may be readily removed for renewal or repair; and wherein the scrubbers or can cleaning members, especially those adapted to clean the interior of the cans, are so constructed that the portions receiving the greater amount of wear can be readily renewed or replaced and placed in proper operative relation with the remainder or main portion of the brush, as will more fully appear from the following detailed description.

A further object of my invention is to provide means whereby the cans may be easily inverted over the interior scrubbers or can cleaning members, and, therefore, with the upper ends of the cans beneath the normal water level in the machine, said means being adapted to convey the inclosed or pocketed air from within the inverted can, and at the same time maintain a constant supply of clean water at the upper surface or water level, both within the cans and to the outside thereof, as will be more fully set forth in the following detailed description thereof.

In the drawings, Figure 1 is a vertical sectional view of my improved machine, illustrating the scrubbers or can cleaning members in side elevation and disclosing an inverted can on one of the scrubbers or can cleaning members, in longitudinal section. Fig. 2 is a top plan view thereof.

Fig. 3 is an end elevation of my improved machine, with the outside bottom scrubbers or cleaning members shown broken away. Fig. 4 is a detailed view of the intermediate or outside scrubber and one of the side or interior scrubbers, showing the same in longitudinal section. Fig. 5 is a vertical sectional view of a portion of the scrubber operating mechanism or driving means taken on the line *a—a* of Fig. 2. Fig. 6 is a vertical sectional view of the upper part of the overflow and air conveying member. Fig. 7 is a bottom plan view of the removable top portion of one of the can scrubbers or members.

In the particular exemplification of my invention, as disclosed in the drawings, 10 represents a tank or receptacle preferably constructed of sheet metal formed so as to contain water during the scrubbing or cleaning of the cans; it being understood, of course, that the tank or receptacle may be made of any size commensurate with the size of the cans for which the machine is intended. The upper part of the tank or receptacle is shown provided with suitable faucets as at 11, whereby both hot and cold water may be allowed to flow into the receptacle from any suitable source of supply with which the faucets may be connected.

The tank or receptacle is preferably formed of sheet metal, and I prefer to provide an apertured casting or member 12, preferably of a single piece, which is adapted to be secured beneath the bottom proper of the receptacle 10 in any suitable manner so as to form a comparatively water-tight connection at points where the aperture and projecting portions of the casting or member register with or extend through apertures formed in the bottom proper of the receptacle. The member 12 may be of any suitable construction and is shown provided with a passage 13 extending longitudinally therethrough, the orifice of said passage being at the ends of the casting or member as very clearly shown in Fig. 1. As shown in Fig. 1, the casting or member 12 is provided with the upwardly extending port 14 and bosses 15 and 16, provided with ports or openings extending through to the upper surface of the member 12 and communicating with the channel or passage 13.

The bosses 15 and 16 are adapted to extend through openings in the bottom proper of receptacle 10, as very clearly shown in

Fig. 1. The ports or openings in bosses 15 and 16 are adapted to receive the ends of the tubes 17 and 18, respectively, which receive the hollow cores or cylindrical portions 19 and 20, in which the bristles of the brushes are secured in any suitable manner, as very clearly shown at 21 in Fig. 4; the bristles of the brushes extend throughout the length of the core of the brush for a distance commensurate with the depth of can for which the machine is intended.

In the particular illustration of the invention, as disclosed in the drawings, I preferably show brushes of different diameters; for example, brush 22 is shown of smaller diameter than brush 23, although both brushes may be of the same diameter if desired. Secured to the lower ends of the cores 19 and 20 of the brushes 22 and 23, are the gears 24 and 25, respectively; the gears being preferably provided with the flange portions or extended hubs, as clearly shown in Fig. 4 at 26, intended to receive the screws or bolts whereby the gears are secured to the cores of the brushes; the lower surfaces of the gears being shown as resting upon the bosses 15 and 16 formed on the member 12 and, therefore, at a slight distance removed from the bottom proper of the receptacle 10.

The gears 24 and 25 are arranged in mesh with the peripheral part of the large gear 27, which is preferably provided with elongated hub portion 27* and is rotatably mounted on the stationary shaft or rod 28 which is preferably secured in the boss 29 of member 12; boss 29 being provided at a point intermediate of bosses 15 and 16, as very clearly shown in Fig. 1.

Mounted on the shaft 28 is a core 30 of the intermediate brush 31. The core of brush 31 rests upon the extended hub 27* of gear 27 and is made to rotate with gear 27 by means of the pins 32, see Fig. 4; the connection between brush 31 and hub 27* being such, however, that the brush 31 may be removed from the shaft 28 when desired.

The core of brush 31, unlike the cores of side brushes 22 and 23, is preferably made to extend over the top of shaft 28 and may be provided with bristles throughout the top thereof. As very clearly shown in Fig. 4, however, the cores of the side brushes 22 and 23 do not extend over the top of the hollow members or tubes 17 and 18, and thus provide orifices at the upper ends of brushes 22 and 23, whereby communication may be effected, by means of the tubes 17 and 18, with the longitudinal passage 18 of member 12.

The gear 27 is also formed on its upper surface in the nature of a bevel gear, which is adapted to mesh with beveled gear 33, see Figs. 2 and 5. Gear 33 is secured to the driven shaft 34, which latter is preferably rotatably mounted in the bracket or support

35 mounted at a suitable point in the bottom of receptacle 10. The shaft 34 extends through the rear wall of receptacle 10 and is provided at its outer end with a belt receiving pulley 36 which is preferably loosely mounted on the shaft so as to be free to rotate thereon without imparting rotation to shaft 34 when rotation of the brushes is not desired.

A clutch mechanism 37 is feathered on shaft 34 so as to move longitudinally thereof and rotate therewith, thus enabling the mechanism to be thrown into clutching engagement with the hub of pulley 36 and impart rotation or power from pulley 36 to shaft 34 when the clutch mechanism is moved into engagement with the pulley. The clutch mechanism 37 may be operated by any suitable means; I show the same controlled by means of lever 38 which is pivotally secured at 39 to a suitable bracket secured on the wall of the receptacle 10, as very clearly shown in Fig. 3. It is evident from the construction shown in Fig. 3, that when the upper end of lever 38 is moved toward the receptacle 10, as shown in that figure, the clutch-mechanism will be in operative engagement with pulley 36; while movement of the upper end of the lever 38 in the opposite direction will move the clutch-mechanism out of clutching engagement with pulley 36.

I prefer to construct the can exterior scrubber 31 and the can-interior scrubbers 22 and 23, with a removable top portion or section as clearly shown at 40 and 40* in Figs. 4 and 7, because the upper portion of these scrubbers or brushes receives more wear and tear than the remainder of the brushes. I have illustrated the sections 40 and 40* having slot and pin connections with the main or body portions of the brushes, in order that the top sections may be removed and replaced by new sections of equal diameter. In the preferred construction, the bottom portions of the cores of the sections 40 and 40* are similarly provided with an annular plate as at 41, see Fig. 7, having the slots 42, preferably arranged diametrically opposite each other, with the ends of the slots presented in opposite directions enlarged, as clearly shown in Fig. 7, to receive the heads of the pins 43 shown in Fig. 4; these pins being secured in the cores of the main or body portions of the brushes. It is clearly evident from the construction shown and described, that when the enlarged portions of the slots 42 are brought to register with the heads of the pins 43, the removable sections 40 and 40* may be put into proper position and with a slight turn of the section, securely locked in place. It will be understood, of course, that the enlarged portions of the slots 42 will not be brought to register with the heads of the pins 43 until the sections 40

and 40° are moved in directions reverse to the directions of rotation of the brushes; the top sections or portions of the brush or brushes will, therefore, remain locked in place during the normal operation or rotation of the brushes.

As previously stated, the member or casting 12 is provided with a port 14, which is preferably flared as shown in Fig. 1, to receive the beveled stopper or valve 44 secured at the lower end of overflow pipe 45. The overflow pipe 45 is held in proper position by means of suitable brackets 46 and 47 and arranged to be moved vertically so that the valve 44 may be removed from its seat, namely orifice 14, and allow the receptacle or tank 10 to be drained, as clearly shown in Fig. 1. Adjacent the upper end of overflow pipe 45, I prefer to provide it with an overflow orifice 45^a, which orifice 5 may be controlled by the sleeve 48 seated in the upper end of overflow pipe 45 and held in proper position by the flange 48^a on the sleeve. The sleeve 48 is provided with an orifice 48^b adapted to register with orifice 45^a, when it is desired to permit the surface water in the tank or receptacle to overflow or gradually drain off through overflow pipe 45, because in the preferred construction of my invention, the overflow pipe is adapted to extend above the normal water level in the receptacle or tank 10, as the pipe 45 is also intended to serve as an air outlet when the cans are inserted in place over the interior scrubbers or brushes 22 and 23.

In order that the pipe or member 45 may be readily moved so as to lift stopper or valve 44 from its seat, I provide a link 49, the upper end whereof is pivotally secured at 49^a to the bell-crank lever 50, the short end or arm whereof is pivotally secured at 50^a to the wall of the receptacle 10, while the link 49 is secured to the lever 50 at a point intermediate of its ends. It is evident from the construction shown and described, that movement of lever 50 about its pivotal point 50^a so as to bring pivotal point 49^a above and substantially in alignment with pivotal point 50^a, will raise overflow pipe 45 upward and maintain the latter in its raised position; while movement of lever 50, so as to bring the pivotal point 49^a to either side of the vertical plane of pivotal point 50^a, will permit the pipe 45 to drop into place.

It is apparent that with the water level in the receptacle at a point slightly above the tops of brushes 22 and 23, when the cans (one of which is indicated at A in Fig. 1) are inverted over the brushes 22 and 23 respectively, the air in the can will be forced toward the bottom of the can, (the bottom being uppermost when the can is put into place for scrubbing) and unless some means are provided whereby this cushion or pocket

of air is permitted to escape, it would be impossible to properly seat the cans in place on the scrubbers or brushes. With my improved construction, the air will be permitted to escape from the can-interior by means of the tubes 17 and 18, respectively, into the passage or channel 13 arranged in member 12, and from thence upward through orifice 14 and out through the top of overflow pipe or member 45, thereby allowing the cans to come to rest on top of the brushes and permit the bristles of the brush to contact with the interior bottom of the can, as well as with the inner side walls thereof.

In addition to the function of providing a proper air vent, it is evident that the tubes 17 and 18, respectively, will also permit the slush and grease, which usually rises to the surface of the water within the can, to escape through the respective tubes 17 and 18 and flow into the passage 13 of member 12 and be discharged by means of the discharge pipe 51 which may lead to a sewer connection.

The passage 13 in member 12 is shown extending from end to end of the member, thus permitting a discharge connection being formed at either one or both ends of the member, if desired; one of the ends of the member being shown closed in Fig. 1 by a suitable screw plug 52, where but one sewer connection is provided.

Pivots secured to the upper ends of the receptacle or tank 10, and at points in alignment with the brushes 22 and 23, I provide the bottom scrubbers 53 and 54; these brushes comprising the handle portions 53^a and 54^a, respectively, of proper length, to which the brushes 53 and 54 are secured; the brushes 53 and 54 being of proper size and adapted to come into contact with the bottoms of the cans when swung downwardly into the horizontal position indicated to the left in Figs. 1 and 2.

The machine is so geared as to give the proper speed to the respective brushes, each of which is preferably made to revolve at a different speed so as to provide the proper scrubbing effect on the walls of the can; the brushes being so arranged as to be in constant contact with the wall of the can at a point where the can extends intermediate of the brushes. For example, the can A, in Figs. 1 and 2, is shown inverted over brush 23, thus bringing the side wall thereof into contact with brush 23 and intermediate brush 31, the former scrubbing the interior while the latter scrubs the exterior. By reason of the different speeds of rotation of the brushes, the can will rotate at a speed differing from that of either brush, and thereby provide frictional contact with the brushes which will cause the can to be thoroughly scrubbed and cleaned throughout the interior and exterior thereof. It is evident

that by maintaining the brushes 53 or 54 into contact with the bottoms of the cans, that the entire bottom will be scrubbed or cleaned during the continued rotation of the 5 can.

With my improved machine, it is evident that not only is it possible to properly seat the cans in place, but that a constant supply of clean water will be maintained both within 10 the cans as well as to the exterior thereof. It is understood, of course, that any suitable means may be provided in discharge-pipe 51 whereby the flow therethrough may be shut-off or controlled during the operation of the 15 machine.

I have shown and described what I believe to be the simplest and best form of my invention, but the same may be modified in certain respects without, however, departing 20 from the spirit of the invention, and I do not wish to be understood, therefore, as limiting myself to the exact construction shown and described.

What I claim is:—

25 1. A can washing machine, comprising a receptacle provided with an outlet, vertically movable means whereby said outlet is controlled, said means being arranged to act as an overflow while seated in place in the 30 outlet, a plurality of vertically disposed brushes or scrubbers, the cores of the brushes being provided with passages extending longitudinally therethrough, a member secured to the bottom of the receptacle 35 and provided with a passage arranged in communication with said outlet and the passages in the cores of the brushes whereby air and water may be conveyed from points adjacent to the upper ends of the brushes or 40 scrubbers, and means whereby the brushes are simultaneously operated.

2. A can washing machine, comprising a receptacle, a plurality of vertically disposed members secured in the bottom of said receptacle, a portion of said members being provided with passages extending longitudinally therethrough from top to bottom, scrubbers or brushes mounted on said members so as to rotate and so related to one another as to contact respectively with the can exterior and interior, a member disposed along the bottom of the receptacle and provided with a passage extending therethrough, said passage being in communication 50 with the members having the longitudinal passages whereby air and water may be conveyed from within the can inverted over the scrubbers or brushes, means whereby the air is permitted to escape from the passage 55 in the member arranged along the bottom of the receptacle and water beyond a predetermined point in the receptacle be permitted to flow into said member, and means whereby the brushes are rotated.

65 3. A can washing machine, comprising a

receptacle provided with an outlet, a vertically movable member arranged to be seated in said outlet and control the flow therethrough, a plurality of brushes rotatably mounted in said receptacle, means arranged 70 concentrically with the brushes and extending to the ends thereof whereby air and water may be conveyed from a point above said brushes, a conduit disposed along the bottom of said receptacle and in communication 75 with said means, and means whereby the brushes are rotated.

4. A can washing machine, comprising a receptacle provided with an outlet in the bottom thereof, a vertically movable open 80 ended member adapted to be seated in the outlet and control the flow therethrough, a plurality of brushes vertically disposed in the receptacle, means extending centrally through the brushes and through the bottom 85 of the receptacle whereby air and water may be conveyed from the tops of the brushes, a conduit arranged along the bottom of the receptacle and in communication with said means and with said outlet whereby the air 90 conveyed through said means is permitted to pass upward through the open ended member seated in the outlet, means whereby the member is controlled, and means whereby the brushes are rotated. 95

5. A can washing machine, comprising a receptacle, provided with an outlet in the bottom thereof, vertically movable means whereby the outlet is controlled, a plurality of vertically disposed brushes mounted on 100 the bottom of the receptacle so as to rotate, a portion of the brushes being provided with passages extending longitudinally therethrough so as to effect communication between the upper part of said brushes and the bottom of the receptacle, means disposed along the bottom of the receptacle and in communication with said passages and with said outlet, and means whereby the brushes may be simultaneously rotated. 105

6. A can washing machine, comprising a receptacle provided with an outlet in the bottom thereof, a plurality of vertically disposed brushes mounted in the bottom of the receptacle so as to rotate, some of the 110 brushes being provided with passages extending longitudinally therethrough so as to establish communication between the tops of the brushes and the bottom of the receptacle, a member disposed along the bottom 115 of the receptacle and provided with a passage having communication with the passages of the brushes and with the outlet of the receptacle, means adapted to control the outflow through said outlet, said means being provided with a passage extending longitudinally therethrough, so as to permit air at the upper ends of the brushes to escape through the passage of said last mentioned means and to constitute an overflow 120

125

for the receptacle, means whereby the first mentioned means may be moved into and out of controlling relation with the outlet of the receptacle, and means whereby the 5 brushes are simultaneously operated.

7. A can washing machine, comprising a fluid-containing receptacle provided with an outlet in the bottom thereof, a plurality of vertically disposed brushes rotatably mounted 10 in the bottom of the receptacle, some of the brushes being adapted to receive inverted cans and to scrub the interiors thereof while the other brush is adapted to contact with and scrub the exteriors of the cans, 15 the brushes adapted to receive the inverted cans being provided with concentric passages extending from the tops of the brushes to the bottom of the receptacle so as to permit the escape of air and water from within 20 in the inverted can, means secured to the lower ends of the brushes whereby they are simultaneously rotated, means secured to the bottom of the receptacle and provided with a passage arranged in communication with 25 the passages of the brushes and in communication with the outlet of the receptacle, and means adapted to extend above the water level in the receptacle and arranged to be normally seated in the outlet 30 of the receptacle so as to control the flow therethrough, said means being arranged to convey the air from the passage in the member beneath the receptacle and permit the same to escape above the water level in the 35 receptacle and to constitute an overflow for the receptacle.

8. A can washing machine comprising a fluid-containing receptacle provided with an outlet, a plurality of vertically disposed 40 brushes rotatably mounted in the bottom of the receptacle, the brushes adapted to extend into the cans to be scrubbed being provided with passages extending from top to bottom thereof so as to convey air and water from

within the cans and in proximity to the upper ends of the brushes, a conduit disposed along the bottom of the receptacle and in communication with the passages of the brushes and the outlet of the receptacle, means extending from the point above the normal water level in the receptacle and into the outlet so as to control the flow through said outlet, said means being adapted to constitute an overflow and air vent, means whereby the brushes are simultaneously rotated at predetermined speeds, and brushes pivotally mounted at the upper end of the receptacle so as to be swung into and out of scrubbing contact with the bottoms of the cans inverted over the brushes. 45 50 55 60

9. A can washing machine, comprising a receptacle provided with an outlet in the bottom thereof, vertically disposed members secured in the bottom of the receptacle, a portion of said members being provided 65 with passages extending from top to bottom, cylindrical brushes removably mounted on said members and adapted to rotate thereon, gearing secured to the lower ends of the brushes whereby they are simultaneously rotated at predetermined speeds, a conduit secured along the bottom of the receptacle and in communication with the passages in said members and the outlet of the receptacle, vertically movable means seated 70 in the outlet of the receptacle and adapted to extend above the normal water level in the receptacle, said means being arranged to act as an air vent and overflow, means whereby the first mentioned means may be 75 controlled and its relation to the outlet of the receptacle determined, and means whereby power is imparted to said gearing. 80
